CHIMNEY FOR LIQUID FUEL BURNERS

Walter B. Engh, Alexandria, Ind., assignor to The
Mantle Lamp Company of America, Chicago,
Ill., a corporation of Illinois

Application March 4, 1939, Serial No. 259,770

24 Claims. (Cl. 126—93)

This invention includes a chimney construction consisting of upper and lower sections for producing desired draft on a liquid fuel burner, so that the fuel may be burned in large quantity and with maximum efficiency, the chimney sections being spaced from each other vertically to produce a check-draft effect to facilitate the removal of the lower chimney section and burner when desired, and also to facilitate producing an oxidizing atmosphere in the upper chimney section to completely burn the oxidizable products of combustion and any vagrant odors and gases that may find their way into the chimney.

One of the objects of the invention is to produce a two part chimney construction for use with a liquid fuel burner, the upper section having fixed support and position excepting for general adjustment in assembling the device, and the lower section being carried by and having fixed relation to a burner movable horizontally to clean or recondition the burner, the upper end of the lower section and the lower end of the upper section having such relation that there is no interference between the adjacent ends of the chimney sections when the lower section is so moved from and into alignment with the upper section, yet at the same time preserving the desired chimney effect as a whole when the sections are in alignment with each other.

In space heating stoves where the products of combustion from the flame exhaust into a room or the space heated, objectionable odors are generally given off, whether the burner operates with a yellow flame or a blue flame. A further object of the invention is to provide a structure and operation practically eliminating these objectionable odors. A chimney draft somewhat greater than would normally be required for the burner is employed and then the excess draft is reduced to a normal amount so the burner will function properly, by the use of a check draft positioned above the flame of the burner, through which fresh air enters into the upper part of the chimney, and there mingles with the hot products of combustion and vagrant odoriferous gases escaping from the burner flame. A highly heated and oxidizing atmosphere is thus produced in the upper portion of the chimney which promotes a secondary combustion to destroy the objectionable gases which would otherwise escape from the chimney into the room.

A further object of the invention is to provide the adjacent ends of the chimney sections with a movable element or more specifically a ring,

carried by one of the sections and automatically cooperating with the other chimney section to secure the desired relationship between the adjacent ends of the chimney sections, and more specifically, where a check draft passage of definite extent is desired, to produce and maintain said passage substantially of the desired extent for changes in adjustment of the chimney sections due to use, and for misalignment of the chimney sections.

A further object of the invention is to construct and support the movable element or ring in a manner to materially increase the entry clearance below the upper chimney section, for the lower chimney section in moving the latter into alignment with the former, over the separation of the adjacent ends of said sections in use, by providing for automatically moving or tilting said member or ring to produce said increased entry clearance.

Generically, it is an object of the invention to make a chimney of the class described, in upper and lower sections substantially in alignment in use, the lower section being movable horizontally from and into said alignment, in which a movable element or more specifically a ring, avoids interference during said horizontal movement and effects substantially constant chimney action for small misalignments of the chimney sections and where desired, provides a check draft passage of definite amount into the chimney and maintains said passage of the desired amount for small changes in the relation of the chimney sections either axially or laterally from their optimum relation, which member or ring may also by its movement increase the entry clearance of the lower chimney section when moving it into alignment with the upper chimney section.

The invention will be best understood by reference to the accompanying drawings illustrating a preferred embodiment thereof, in which:

Fig. 1 illustrates an enclosed stove equipped with the chimney construction of the invention, in front elevation, the stove being provided with a removable cover which is shown in place in this figure.

Fig. 2 shows in side elevation the structure illustrated in Fig. 1.

Fig. 3 is a top view of the device with the removable cover in place.

Fig. 4 is a top view of the device with the cover removed.

Fig. 5 is a vertical sectional view through the device, taken along the line 5—5 in Fig. 1.

Figs. 6, 7 and 8 are horizontal sectional views through the device, taken respectively along the lines 6—6, 7—7 and 8—8 in Fig. 1.

Fig. 9 shows in an enlarged view similar to Fig. 5, the upper portion of the lower chimney section and the adjacent portion of the upper chimney section.

Fig. 10 shows in a view similar to Fig. 9, the relation of the movable device on the upper chimney section, when the lower chimney section is removed from alignment with the upper chimney section, and

Fig. 11 is a horizontal sectional view through the structure taken along the line 11—11 in Fig. 9.

Similar numerals refer to similar parts throughout the several views.

As shown in Figs. 1 and 2, the illustrated structure consists of a sheet metal casing 10 having front, back and side walls in which vertical apertures 11 are formed to permit the flow of air into or from the casing, as may be required during the operation of the burner. In the lower portion of the front wall of the casing 10 a door 12 is provided which is mounted on pivotal supports 13 and 14, the casing being supported on base portions 15. The casing is provided with a removable sheet metal cover 16 provided with front, back and side walls containing perforations 17 to permit the egress of the hot gases resulting from the operation of the device. As shown in Fig. 3, the cover 16 is provided in its top surface with perforations 18 which also permit the egress of the hot gases resulting from the operation of the device. As shown in Fig. 4, the upper end of the casing 10 below the cover 16 is provided with a top wall 19 supporting in its central portion a grating 20 for cooking purposes, so that with the cover 16 removed, the device may be used as a cooking stove, whereas if it is to be used as a heating stove, the cover 16 is preferably put in place to give the device a better appearance and provide for a more effective distribution of the heated gases than is possible with the arrangement of the device which is most effective for cooking purposes. The top wall 19 is provided with apertures 21 around the grating 20 to permit the escape of the heated air in the casing 10 around the chimney structure.

As shown in Fig. 5, the casing 10 supports centrally therein and in its upper portion, an upper chimney section 22, so that the said chimney section is in alignment with the grating 20. The lower end portion of the chimney section 22 is engaged by a clamping band 23 provided, as more clearly shown in Fig. 6, with arms 24 supported at their outer ends by the side walls of the casing 10. The clamping ring 23 is held in place against the chimney section 22 by clamping screws as indicated, which screws are connected with the lower ends of inclined bracing rods 25 extending to the upper outer portion of the casing to which they are secured, as indicated in Fig. 1. In this manner the upper chimney section 22 receives fixed support at its lower end, from the casing 10, and in assembling the parts, the chimney section may be moved vertically in the clamping ring 23 to properly locate its lower end relatively to the upper end of the lower chimney section 26, and then the section 22 may be rigidly clamped in that position. This imparts a fixed support to the lower end of the chimney section 22 adjacent the check-draft passage, so that any expansion or con-

traction of the lower chimney section 22, which is due to heating or cooling the same, results in vertical movement of the upper end of the chimney section relatively to the casing. To permit this relative movement, the top wall 19 of the casing is provided with wings 27 extending downwardly from the edge of the opening made to receive the grating 20, so that the lower portions of said wings lightly engage the outer surface of the upper end portion of the chimney section 22, to hold said upper end portion in vertical position, and at the same time to permit expansion or contraction vertically of said upper end portion.

The lower portion of the casing 10 is provided with horizontal channel-shaped guideways 28 to engage the side portions of a liquid fuel tank or reservoir 29, which carries a burner 36 to the upper portion 36a of which the lower edge portion of the lower chimney section 26 is rigidly secured, for example by spot welding. The rear ends of the guideway members 28 have secured to them a cross-bar 28a to engage the tank 29 when it is moved rearwardly sufficiently to bring the chimney sections into alignment with each other. The chimney section 26 is provided at its lower edge as more clearly shown in Fig. 9, with an outwardly extending flange 26a provided with spacing lugs 26b which produce a fixed separation between the flange 26a and a horizontal flange 36b constituting a part of the burner structure. This insures the admission of a definite amount of air to the burner under the lower edge portion of the chimney section 26 which passes upwardly in the chimney sections 26 around the flame produced by the burner. The burner flange 36b is preferably rigidly secured to the upper portion 36a of the burner shell, for example, by spot welding. To give the lower chimney section 26 a fixed position relatively to the burner, said lower chimney section is preferably rigidly secured to the burner shell, for example, by spot welding the lugs 26b of the lower chimney section to the burner flange 36b.

The chimney section 26 is preferably of sheet metal and is provided at its upper edge with an integral and inwardly extending horizontal flange 26c on which lugs 30a connected with the upper chimney section 22, rest. The upper chimney section 22 adjacent its lower end is provided with inwardly extending pivots 31 extending through short vertical clearance slots 30b formed in a tubular device 30 carried by the lower end portion of the chimney section 22. The device 30 is provided with a horizontal flange portion 30c at its lower end, which is preferably integral with the tubular portion of the device and extends outwardly and horizontally therefrom so that it may occupy a position substantially parallel with the upper surface of the flange 26c. The lugs 30a are formed downwardly from the flange 30c. As shown in Fig. 11, the pivots 31 are slightly in front of the diameter of the lower chimney section which extends from side to side thereof, as a result of which the major portion of the weight of the movable device 30 is back of its pivotal supports, so that when the lower chimney section 26 is moved from alignment with the upper chimney section 22, as illustrated in Fig. 10, the front or entry portion of the flange 30c is raised substantially above the position it occupies during the operation of the device, thereby affording ample entry clearance for the lower chimney section 26, so that interference or catching and injury of the parts, is

practically impossible when the lower chimney section is moved towards the rear of the structure in moving the reservoir 29 into operative position in the casing and at the same time moving the lower chimney section 26 substantially into alignment with the upper chimney section 22. As a result of the construction described however, when the lower chimney section has been moved under the movable device 30 substantially half way to its operating position, the movable device rests on the flange 26c, the lugs 30a as illustrated in Fig. 11 being so disposed that they are always above some portion of the flange 26c, as the movement of the lower chimney section 26 is completed to its operating position. It will be noted that there is a substantial clearance space between the lower end of the chimney section 22 and the flange 30c, to permit the substantial tilting of the movable member 30 illustrated in Fig. 10, when the lower chimney section 26 is removed from alignment with the upper chimney section 22.

The lower chimney section 26 is provided in its front wall with a sight opening 26d which is closed by a sheet of transparent heat-resistant material 32, for example mica, which is held in place by a frame 33 secured to the chimney section 26, to afford a visible indication of the operation of the burner of the device.

As shown in Fig. 5, the cover 16 is preferably provided with a baffle plate 34 over the upper end of the chimney section 22, to distribute the highly heated gases delivered from the upper end of said chimney section.

The cooperating parts at the upper end of the lower chimney section 26, determine a check-draft passageway 35 between the flange 26c and the flange 30c, the vertical extent of which passageway is determined by the amount of projection of the lugs 30a from the flange 30c. To permit the tilting action illustrated in Fig. 10, the tubular portion of the movable device 30 must be a correspondingly loose fit in the lower portion of the upper chimney section 22, which results in a small amount of air flow into the upper chimney section 22 between its lower end portion and the outer surface of the tubular device 30, which, however, is substantially constant and is compensated for by so selecting the vertical height of the passageway 35 that the total check-draft effect is of the desired amount.

The movable device 30 thus not only provides a construction which makes the entry of the lower chimney section to its operative position a simple matter, requiring no thought or attention from the operator, but it also where desired, automatically insures a check-draft effect of definite amount, which is found to be effective in connection with securing complete combustion of the fuel, of the incomplete products of combustion, and of vagrant and noxious fumes that may find their way into the chimney. This accomplishes a two-fold effect, (1) it results in complete combustion of the liquid fuel and therefore the production of the maximum possible quantity of heat for a given quantity of fuel, and (2) it discharges heated gases from the device which are not in any way unpleasant or offensive. In cases where the check-draft is small, or is not desired, the lugs 30a may be correspondingly small, or may be omitted.

While I have shown my invention in the particular embodiment above described, it is understood that I do not limit myself thereto as I may.

employ equivalents thereof without departing from the scope of the appended claims.

Having thus described my invention, what I claim is:

1. A device for burning liquid fuel including in combination a fuel reservoir, a burner carried by said reservoir, a lower chimney section carried by said burner, an upper chimney section having fixed support, means supporting said reservoir for horizontal movement, whereby said lower chimney section may be moved into and from alignment with said upper chimney section, there being a check-draft passageway into the chimney at the upper end of said lower chimney section, and tilting means carried by one of said adjacent chimney end portions substantially increasing the entry clearance vertically between said chimney end portions when said lower chimney section is removed from below said upper chimney section. 20

2. A device for burning liquid fuel including in combination a fuel reservoir, a burner carried by said reservoir, a lower chimney section carried by said burner, an upper chimney section having fixed support, means supporting said reservoir for horizontal movement, whereby said lower chimney section may be moved into and from alignment with said upper chimney section, there being a check-draft passageway into the chimney at the upper end of said lower chimney section, and tilting means carried by one of said adjacent chimney end portions substantially increasing the entry clearance vertically between said chimney end portions when said lower chimney section is removed from below said upper chimney section, said tilting means having vertically movable connection with the chimney portion supporting it maintaining a fixed effective check-draft spacing between said adjacent end portions for variances in vertical spacing of said upper chimney section from said burner. 30

3. A device for burning liquid fuel including in combination a fuel reservoir, a burner carried by said reservoir, a lower chimney section carried by said burner, an upper chimney section having fixed support, means supporting said reservoir for horizontal movement, whereby said lower chimney section may be moved into and from alignment with said upper chimney section, there being a check-draft passageway into the chimney at the upper end of said lower chimney section, a ring loosely fitting the lower end of said upper chimney section, and pivotal connections between said ring and said upper chimney section, said ring having greater weight back of than in front of said pivotal connections tending to tilt the front portion of said ring upwardly, the upper end portion of said lower chimney section having engagement with and spaced from said ring to form said check-draft passageway. 50

4. A device for burning liquid fuel including in combination a fuel reservoir, a burner carried by said reservoir, a lower chimney section carried by said burner, an upper chimney section having fixed support, means supporting said reservoir for horizontal movement, whereby said lower chimney section may be moved into and from alignment with said upper chimney section, there being a check-draft passageway into the chimney at the upper end of said lower chimney section, a ring loosely fitting the lower end of said upper chimney section, and pivotal connections between said ring and said upper chimney section, said ring having greater weight back 60

carried by and having vertical movement relatively to said upper section, said ring having vertically loose pivotal connection with said upper section in front of the center of gravity of said ring tending to tilt the front portion of said ring upwardly to increase the entry clearance of said lower section.

12. In combination, an upper chimney section having fixed position, a lower chimney section movable horizontally into and from alignment with said upper chimney section and forming a check-draft passageway between said sections when said sections are substantially in alignment with each other, and means maintaining said passageway substantially constant for different vertical positions of said upper section relatively to said lower section, said means including a ring carried by and having vertical movement relatively to said upper section, said ring having a first horizontal flange and said lower section having a second horizontal flange, said flanges cooperating to define said check-draft passageway, said ring having vertically loose pivotal connection with said upper section in front of the center of gravity of said ring tending to tilt the front portion of said ring upwardly to increase the entry clearance of said lower section.

13. In combination, an upper chimney section having fixed position, a lower chimney section movable horizontally into and from alignment with said upper chimney section, and a ring pivotally connected with the lower end portion of said upper chimney section and extending below the lower end of said upper chimney section, the pivotal connection of said ring being laterally displaced from the center of gravity of said ring and towards the entry position of said lower chimney section, whereby said ring is tilted and the entry clearance for said lower chimney section is substantially increased when said lower chimney section is moved from below said upper chimney section.

14. In combination, an upper chimney section having fixed position, a lower chimney section movable horizontally into and from alignment with said upper chimney section, and a ring pivotally connected with the lower end portion of said upper chimney section and extending below the lower end of said upper chimney section, the pivotal connection of said ring being laterally displaced from the center of gravity of said ring and towards the entry position of said lower chimney section, whereby said ring is tilted and the entry clearance for said lower chimney section is substantially increased when said lower chimney section is moved from below said upper chimney section, said lower chimney section having a flange extending horizontally from its upper end for cooperation with said ring.

15. In combination, an upper chimney section having fixed position, a lower chimney section movable horizontally into and from alignment with said upper chimney section, and a ring pivotally connected with the lower end portion of said upper chimney section and extending below the lower end of said upper chimney section, the pivotal connection of said ring being laterally displaced from the center of gravity of said ring and towards the entry position of said lower chimney section, whereby said ring is tilted and the entry clearance for said lower chimney section is substantially increased when said lower chimney section is moved from below said upper chimney section, said ring having a flange ex-

tending horizontally from its lower end for cooperation with said lower chimney section.

16. In combination, an upper chimney section having fixed position, a lower chimney section movable horizontally into and from alignment with said upper chimney section, and a ring pivotally connected with the lower end portion of said upper chimney section and extending below the lower end of said upper chimney section, the pivotal connection of said ring being laterally displaced from the center of gravity of said ring and towards the entry position of said lower chimney section, whereby said ring is tilted and the entry clearance for said lower chimney section is substantially increased when said lower chimney section is moved from below said upper chimney section, said ring having a flange extending horizontally from its lower end, and said lower chimney section having a flange extending horizontally from its upper end for cooperation with said ring flange.

17. In combination, an upper chimney section having fixed position, a lower chimney section movable horizontally into and from alignment with said upper chimney section, and a ring pivotally connected with the lower end portion of said upper chimney section and extending below the lower end of said upper chimney section, the pivotal connection of said ring being laterally displaced from the center of gravity of said ring and towards the entry position of said lower chimney section, whereby said ring is tilted and the entry clearance for said lower chimney section is substantially increased when said lower chimney section is moved from below said upper chimney section, said pivotal connections being loosely connected vertically whereby said ring is capable of limited vertical movement relatively to said upper chimney section.

18. In combination, an upper chimney section having fixed position, a lower chimney section movable horizontally into and from alignment with said upper chimney section, and a ring pivotally connected with the lower end portion of said upper chimney section and extending below the lower end of said upper chimney section, the pivotal connection of said ring being laterally displaced from the center of gravity of said ring and towards the entry position of said lower chimney section, whereby said ring is tilted and the entry clearance for said lower chimney section is substantially increased when said lower chimney section is moved from below said upper chimney section, said pivotal connections being loosely connected vertically whereby said ring is capable of limited vertical movement relatively to said upper chimney section, said lower chimney section having a flange extending horizontally from its upper end for cooperation with said ring.

19. In combination, an upper chimney section having fixed position, a lower chimney section movable horizontally into and from alignment with said upper chimney section, and a ring pivotally connected with the lower end portion of said upper chimney section and extending below the lower end of said upper chimney section, the pivotal connection of said ring being laterally displaced from the center of gravity of said ring and towards the entry position of said lower chimney section, whereby said ring is tilted and the entry clearance for said lower chimney section is substantially increased when said lower chimney section is moved from below said upper chimney section, said pivotal connections being

loosely connected vertically whereby said ring is capable of limited vertical movement relatively to said upper chimney section, said ring having a flange extending horizontally from its lower end for cooperation with said lower chimney section.

20. In combination, an upper chimney section having fixed position, a lower chimney section movable horizontally into and from alignment 10 with said upper chimney section, and a ring pivotally connected with the lower end portion of said upper chimney section and extending below the lower end of said upper chimney section, the pivotal connection of said ring being laterally 15 displaced from the center of gravity of said ring and towards the entry position of said lower chimney section, whereby said ring is tilted and the entry clearance for said lower chimney section is substantially increased when said lower 20 chimney section is moved from below said upper chimney section, said pivotal connections being loosely connected vertically whereby said ring is capable of limited vertical movement relatively to said upper chimney section, said ring having a flange extending horizontally from its lower end, and said lower chimney section having a flange extending horizontally from its upper end for cooperation with said ring flange.
21. In combination, an upper chimney section 30 having fixed position, a lower chimney section confined to horizontal movement into and from alignment with said upper chimney section, and a movable sleeve substantially coaxial with and adjacent the end of one of said chimney sections 35 and actuated by engagement with the other of said chimney sections during horizontal movement of said lower chimney section to provide a check-draft passageway of predetermined size into the chimney, said sleeve being mounted for free movement vertically to compensate for mal-adjustment of the chimney sections.
22. In combination, an upper chimney section 40

having fixed position, a lower chimney section confined to horizontal movement into and from alignment with said upper chimney section, and a movable sleeve substantially coaxial with and adjacent the end of one of said chimney sections 5 and actuated by engagement with the other of said chimney sections during horizontal movement of said lower chimney section to provide a check-draft passageway of predetermined size into the chimney, said sleeve being mounted for free movement vertically to compensate for mal-adjustment of the chimney sections.

23. In combination, an upper chimney section having fixed position, a lower chimney section 15 confined to horizontal movement into and from alignment with said upper chimney section, and a movable sleeve substantially coaxial with and adjacent the end of one of said chimney sections 20 and actuated by engagement with the other of said chimney sections during horizontal movement of said lower chimney section to provide a check-draft passageway of predetermined size 25 into the chimney, said sleeve having spacing lugs determining the height of said check-draft passageway.

24. In combination, an upper chimney section having fixed position, a lower chimney section 30 confined to horizontal movement into and from alignment with said upper chimney section, and a movable sleeve substantially coaxial with and adjacent the end of one of said chimney sections 35 and actuated by engagement with the other of said chimney sections during horizontal movement of said lower chimney section to provide a check-draft passageway of predetermined size 40 into the chimney, said sleeve and said other chimney section having horizontally extending flanges cooperating to establish said check-draft passageway.

WALTER B. ENGH. 40
